Attorney.

UNITED STATES PATENT OFFICE.

ROY E. COOK, OF GRAND RAPIDS, MICHIGAN.

LOCKING DEVICE.

Application filed August 17, 1921. Serial No. 492,886.

To all whom it may concern:

Be it known that I, Roy E. Cook, a citizen of the United States, residing at Grand Rapids, in the county of Kent and State 5 of Michigan, have invented new and useful Improvements in Locking Devices, of which the following is a specification.

The present invention relates to locking devices, for connecting and drawing together 10 members of furniture and the like; and its object is to provide a simple, economically constructed, readily installed, very efficient and easily operated device of that character.

This object is attained by, and the invention finds preferable embodiment in, the structure hereinafter particularly described in the body of this specification and illustrated by the accompanying drawings, in which:

20 Figure 1 is a face view of my locking device applied to the post and side rail of a bedstead, the post being shown in vertical section and the device in locking position;

25 Figure 2 is a sectional view of the same taken on a vertical plane corresponding to line 2—2 of Figure 1;

Figure 3 is a top plan view of the same, the post and rail of the bedstead being shown in horizontal section taken on a plane 30 corresponding to line 3—3 of Figure 1;

Figure 4 is a top plan view of the device shown in unlocking position;

Figure 5 is a face view of the same in like position;

35 Figure 6 is a face view of the blank from which the device's supporting plate is formed, the lines on which portions thereof are to be bent to form the plate being indicated in dotted lines; and

40 Figure 7 is an end view of said plate as formed by bending said portions.

In Figures 1, 2 and 3 my device is shown applied to the furniture members 1 and 2, the former being a bed post and the latter 45 being a side rail of a bedstead, the device serving to detachably connect and draw together said members. The post 1 has a recess 3 and a keeper 4 therein, being a fixed rod extending horizontally across the recess as particularly shown in Figures 1 and 3.

50 My device is carried by the other furniture member—the bed rail 2—and is seated in a horizontally extending recess 5 in the rail's inner side, and 55 comprises a metal plate 6 held in said

recess 5 as by screws 7, the plate being snugly fitted laterally, i. e., at its top and bottom edges, between the upper and lower sides of said recess, and being thus held against lateral movement, up or down, by 60 the engagement therewith of the said sides of the recess which thus reinforce the holding effect of the screws. A locking bolt 8 has a hooked outer end 9 adapted to lockingly engage and unlockingly release the 65 keeper 4 and an outer portion 10 and an inner portion 11, which are offset from each other as shown, and an inclined portion 12 intermediate the portions 10 and 11. The outer portion 10 is movable slidably in its 70 longitudinal direction in a slide bearing on the plate 6, such bearing being formed by bending first outwardly and then toward each other the portions 13, 14 of the blank 15 (Figure 6) from which the plate 6 is formed. 75

When the bolt is moved outwardly from its locking position seen in Figures 1 and 3, its outer portion 10 slides longitudinally in said bearing; and as the outward movement of the bolt continues, its inclined intermediate portion 12 passes into this bearing, thereby moving the bolt longitudinally and upwardly laterally into its position seen in Figure 5 wherein the keeper is released. The opposite movement of the bolt, of 85 course, causes the bolt to lockingly engage the keeper and to draw the members 1 and 2 tightly together. A bearing is provided also for the inner portion 11 of the bolt in which it moves longitudinally, such bearing being 90 the portions 16, 17 of the plate 6, to form which bearing said portions of the blank 15 are bent as indicated in Figures 6 and 7.

The bolt is moved outwardly and inwardly into unlocking and locking positions by a 95 lever 18 fulcrumed at 19 on an outwardly extending fulcrum-carrying portion 20 of the plate, such portion being bent as indicated in Figures 6 and 7. A link 21, pivoted at 22 to said lever and at 23 to an outwardly bent portion 24 of the bolt, serves to transmit locking and unlocking movement from the lever to the bolt. The lever has an upwardly bent handle 25.

It will be seen that my device may be 105 very economically manufactured from die-cast sheet metal; may be readily applied to the furniture members; when so applied the plate is securely held against lateral up and down movement by the sides of the recess 110

5; and that the device is easily operated to connect and draw together the members 1 and 2, and oppositely to disconnect them.

Dowels 26 are desirably provided, carried 5 by one member (as 2) and removably seated in sockets 27 in the other member (as 1).

The invention being intended to be pointed out in the claims, is not to be limited to or by details of construction of the particular embodiment thereof illustrated by the drawings or hereinbefore described.

I claim:

1. In combination with a first member having a keeper and a second member, a 15 device of the character described comprising; a bolt movable part way longitudinally and another part way longitudinally and laterally in a bearing on the second member into and out of locking engagement with 20 the keeper.

2. In combination with a first member having a keeper and a second member, a device of the character described comprising; a bolt; a plate carried by the second member and having a bearing in which the bolt is 25 movable part way longitudinally and another part way longitudinally and laterally into and out of locking engagement with the keeper; a lever fulcrumed on the second member; a link pivoted on the lever and on the bolt for moving the bolt.

3. In combination with a first member having a keeper and a second member, a device of the character described comprising; a bolt movable into and out of locking engagement with the keeper and having outer 35 and inner laterally-offset portions and an inclined intermediate portion; a plate carried by the second member and having a bearing in which at least one of the offset portions is in a portion of the bolt's movement longitudinally slid able and in which bearing the inclined portion is slid able in another portion of the bolt's movement; a 40 lever fulcrumed on the second member; a link pivoted on the lever and on the bolt for moving the bolt.

4. In combination with a first member having a keeper and a second member; a 45 device of the character described comprising; a bolt movable into and out of locking

engagement with the keeper and having outer and inner laterally-offset portions and an inclined intermediate portion; a plate carried by the second member and having 55 a bearing in which one of the offset portions is in a portion of the bolt's movement longitudinally slid able and in which bearing the inclined portion is slid able in another portion of the bolt's movement, and having 60 also a bearing in which the other offset portion is slid able; a lever fulcrumed on the second member; a link pivoted on the lever and on the bolt for moving the bolt.

5. In combination with a first member having a keeper and a second member having 65 a recess, a device of the character described comprising; a bolt; a plate seated in and held against lateral movement by the second member's recess and having a bearing 70 in which the bolt is movable part way longitudinally and another part way longitudinally and laterally into and out of locking engagement with the keeper; a lever fulcrumed on the second member; a link pivoted 75 on the lever and on the bolt for moving the bolt.

6. In combination with a first member having a keeper and a second member, a device of the character described comprising; a bolt movable into and out of locking engagement with the keeper and having outer and inner laterally-offset portions and an inclined intermediate portion; a plate carried by the second member and having 80 a fulcrum-carrying portion and a bearing in which one of the offset portions is in a portion of the bolt's movement longitudinally slid able and in which bearing the inclined portion is slid able in another portion of the bolt's movement, and having 85 also a bearing in which the other offset portion is slid able, said fulcrum-carrying portion and said bearings being formed by bending edges of the plate; a lever fulcrumed on said fulcrum-carrying portion; a 90 link pivoted on the lever and on the bolt for moving the bolt.

In testimony whereof I have hereunto set my hand at Grand Rapids, Michigan, this 100 12th day of August, 1921.

ROY E. COOK.
